UNITED STATES PATENT OFFICE.

FRANK G. JOHNSON, OF NEW YORK, N. Y.

REGENERATIVE GAS-BURNER.

SPECIFICATION forming part of Letters Patent No. 398,404, dated February 26, 1889.

Application filed February 15, 1888. Serial No. 264,118. (No model.)

To all whom it may concern:

Be it known that I, FRANK G. JOHNSON, a citizen of the United States, residing in the city, county, and State of New York, have invented a new and useful Improvement in Illuminating-Gas Heaters, of which the following is a specification.

My invention relates to the heating of illuminating-gas at or near the point of consumption, for the purpose of increasing its luminosity when burned, which I accomplish by causing the gas to pass through a long tortuous passage located just above the blaze of the gas and in the heat thereof, whereby it (the gas) becomes intensely heated and when ignited far more luminous. I am aware that devices for this purpose have been heretofore employed; but the special object of my invention is to more intensely heat the gas than has been heretofore accomplished, as the more it is heated the greater becomes its luminosity. I attain this object by means of the device illustrated in the accompanying drawings, in which—

Figure 1 is a transverse section on the line $x x$ of Fig. 4; Figs. 2 and 3, interior views of the two corresponding right and left parts of the device, showing the course of the passage through which the gas passes from the point of ingress to the point of egress, which two parts, when joined together, exactly correspond; Fig. 4, a diaphragm of thin sheet metal which completely separates the two parts, (shown by Figs. 2 and 3,) except it (the diaphragm) has a communicating passage, d ; and Fig. 5, a partial transverse section on the line $y y$ of Fig. 4, showing the communicating passage d through the diaphragm.

Similar letters refer to similar parts throughout the several views.

A is the supply gas-pipe; A' , the pipe, which conveys the gas to the burners underneath and after it passes through the apparatus; B , the right-hand part, and C the left-hand part, of the device; D , the thin diaphragm, (made, preferably, of thin sheet-copper;) $e e$, Fig. 5, one of a series of rivets for securely fastening the two parts BC together, as further indicated by several holes in the outer rim of Figs. 2 and 3; d , an opening or hole in the diaphragm D , which constitutes

the only communication between the said right and left parts, $B C$. $b' b' b'$, Fig. 3, and $c' c' c'$, Fig. 2, are a series of partition-ribs, which alternately terminate on the partition-line $c'' c''$, Fig. 2, between which partition-ribs (in both parts $B C$) are the tortuous passages wherein the gas passes through the device to become heated. b , Fig. 3, is the opening through which the gas passes from the supply-pipe A into the upper half, B , of the device; and c , Fig. 2, the opening through which the gas passes out of the left-hand part C .

It will now be seen that if the right part, B , is turned over and laid upon the left part, C , the partition-ribs $b' b''$, and the central ingress-opening b of part B will exactly register with the partition-ribs $c' c''$ and the central egress-opening c of part C . If now the diaphragm $D D$, Fig. 4, be placed between the parts B and C , so that the communicating opening d in and through the diaphragm $D D$ falls at d' in the parts B and C (seen in Figs. 2 and 3) and the two parts B and C be tightly riveted together, then no gas can enter and pass out of and through the apparatus without entering from the supply-pipe A into and through the ingress-opening b , Fig. 3, and passing around and around back and forth, as indicated by the arrow at d in Fig. 5, and so into the lower or left part, C , of the device, whence it passes around and around back and forth to the egress-opening c into the pipe A' , Fig. 2, as indicated by the arrows, which from ingress to egress causes the gas to be submitted to the heat of its flame while it passes through the tortuous passage between the tortuous partition of the two parts B and C , first, from the center to the circumference in the right part, B , and then in the reverse direction back from the circumference to the center in the left part, C , which in a perpendicular distance of half an inch submits the gas to the heat of its flame through a tortuous horizontal passage of six feet or so in length, while by an increase of the diameter of the apparatus these tortuous horizontal passages may be greatly extended, according to the number of gas-jets to be supplied.

To still further utilize the heat of the burning gas for the purpose of intensifying its luminosity when burned, I employ a cover, E

E, Fig. 1, which is placed over the device above described. This cover consists of an inverted cap spun or stamped out of a single piece of sheet copper or brass, or other suitable metal, which will stand intense heat, which, as shown in Fig. 1, is placed over the above-described apparatus, so as to leave a space between it and the cap both on top and sides, and extending down on the sides some distance below the device above described.

The cap E subserves the twofold purpose of, first, concentrating and retaining the heated air in contact with the plates B C, and, second, of partially enveloping and concealing said plates, which are preferably formed of cast-iron, which is durable, but not ornamental in appearance.

In the formation of the tortuous ribs and resultant gas-passages I do not limit myself to any particular form of the same, as they may be variously arranged to accomplish the same results without materially affecting what I claim as new and useful. I am aware, however, that heating illuminating-gas by the heat of its own combustion is not new, as shown, for instance, by Patent No. 66,153, granted to John H. Erwin, June 25, 1867.

I do not claim, broadly, the heating of illuminating-gas by its own combustion irrespective of the method employed; but

What I do claim as new and useful, and desire to secure by Letters Patent, is—

1. In an illuminating-gas heater, the combination of the corresponding right and left parts, B and C, provided with a continuous tortuous rib from center to circumference, forming a corresponding continuous tortuous gas-passage from center to circumference, and the diaphragm D, having the communicating opening d, substantially in the manner and for the purposes set forth.

2. In an illuminating-gas heater, the combination of the corresponding right and left parts, B and C, provided with a continuous tortuous rib from center to circumference, forming a corresponding continuous tortuous gas-passage from center to circumference, and the diaphragm D, having the communicating opening d and cap E, substantially in the manner and for the purpose described.

FRANK G. JOHNSON.
